SANDWICH BUN SLICER

Benjamin Franklin Smith, Walter Edison Smith,
and Wayne Clayton Broyles, Fort Smith, Ark.

Application August 21, 1934, Serial No. 740,824

2 Claims. (Cl. 146—151)

This invention relates to apparatus for slicing bakery products, and in particular to apparatus for mechanically halving rolls such as sandwich buns. An object of the invention is the provision of a machine for expeditiously halving a plurality of sandwich buns such as are used for barbecue and hamburger sandwiches and the like. Another object is the provision of a machine of such character having means for automatically 10 positioning the buns with respect to the cutting element, and having means for carrying the buns into contact with and past the cutting element to a discharge point. Other objects will be apparent from the description.

The present disclosure constitutes an embodiment of the best means we have thus far devised for reducing the invention to practice, and it is to be understood that the specific details as shown and described shall not constitute limitations inconsistent with the scope of the invention as claimed.

In the drawings—

Figure 1 is a side elevation of a machine as constructed in accordance with the principles of the invention.

Figure 2 is an end view thereof.

Figure 3 is a top plan view of the machine.

Figure 4 is a section taken on line 4—4 of Figure 3.

Figure 5 is a section taken on line 5—5 of Figure 3.

Figure 6 is a vertical section through the knife assembly of the machine.

Figure 7 is a perspective view of the knife blade assembly.

Figure 8 is a fragmentary section illustrating a structural detail.

In detail the machine comprises a table frame consisting of legs 9 supporting a pair of parallel side bars 10 between the opposite ends of which are journalled rollers 11 carrying an endless conveyor belt 12 which operates between the side bars to form a moving top for the table. The legs 9 are suitably braced as by cross bracing 13 at the ends and a longitudinal brace 14. The frame is further strengthened by a foot piece 15 suitably secured to the lower ends of the legs and extending laterally at one side of the frame, their extended ends being connected with the adjacent side bar by inclined brace bars 16.

The longitudinal brace 14 provides a platform supporting a power source, such as an electric motor 17 having a belt drive connection 18 with a driven pulley 19 fixed to a horizontal shaft 20 disposed longitudinally of the frame and journalled

in bearings 21 carried by brackets 22 extending laterally from the brace 14 at the side braced by the members 16. The belt 12 extends beneath the frame over an idler roller 23 supported transversely between the legs at one end of the frame. The belt 12 is driven from an end roller 11, the axle of which extends through the side bar as at 24 and carries a fixed pulley 25 having a belt drive connection 26 to a pulley 27 fixed on a stub shaft 28 journalled in a bearing 29 carried by a support 30 on the adjacent frame legs. The shaft 28 has fixed thereto at one end a bevel gear 31 in mesh with an end pinion 32 fixed on the shaft 20 whereby the drive from shaft 20 is imparted to the end roller and conveyor belt 12 as the motor 17 is operated.

Adjacent the driven end roller 11 each of the frame side bars 10 is provided on its upper face with a longitudinally spaced pair of upright threaded stems 33 surrounded by coil expansion springs 34 which support ears 35 extending from the ends of a rectangular frame 36, the ears being apertured to slide freely on and over the stems 33. This arrangement provides a floating mount for the frame 36 which is spaced above the side bars 10 on the springs, its height above the bars and the conveyor belt 12 being regulated by tensioning nuts 37 on the stems. The end rollers 11 are so placed that the top flight of the conveyor belt 12 runs substantially flush with the upper faces of the side bars 10.

The frame 36 supports a plurality of loose running fluted rollers 38, preferably three, which extend transversely across the conveyor belt in parallel slightly spaced relation. In the clearance between the bottom of frame 36 and the side bars 10, and substantially between the two foremost rollers 38 respecting the feed end F of the machine, is disposed a reciprocatory cutter element 39, such as a slicing knife having a thin flat blade with a serrated edge 40, which extends transversely of the machine parallel to the rollers 38 with its ends extending laterally beyond each side bar 10. The knife is carried at its ends in upright arms 41 on a cutter bar 42 provided with lateral slides 43 that work through guideways 44 carried on a platform 45 forming a part of the table frame and extending transversely across and beyond the opposite sides beneath the side bars 10, which bars are recessed from their under faces as at 46 to accommodate the cutter bar 42. At the drive side of the machine the cutter bar arm 41 has a pitman connection 47 with a crank stud 48 on a counterweighted wheel 49 fixed to one end of a shaft 50 journalled in a bearing 51

carried by the platform 45, which shaft has fixed to its other end a pulley 52 having a belt drive connection 53 with a pulley 54 fixed on the shaft 20 whereby as shaft 20 is rotated the driving connection just described will effect reciprocation of the cutter bar and knife. A brace 55 from the longitudinal brace 14 provides adequate support for the extension of platform 45.

Longitudinal guides 56 are provided at each side of the conveyor belt 12 over its major extent from the feed end F, being carried by slide brackets 57 adjustably mounted at appropriate intervals on the upper faces of the frame side bars.

In service, a desired number of sandwich buns 15 are placed on the conveyor belt and the machine set in operation, the drive being such as to advance the conveyor from the feed end F to the discharge end D. As they approach the cutter assembly the buns are engaged by the foremost 20 roller 38 which presses the buns firmly on the conveyor belt thus insuring positive movement to the knife 39 which reciprocates and cuts the buns in half. Before halving is completed the buns are engaged by the middle roller 38 insuring 25 positive movement completely past the knife, whence they pass to the rearmost roller and are delivered to the discharge end D of the machine.

without separation and misalignment of the two halves.

We claim:

1. In a sandwich bun slicing machine, a conveyor, a halving knife extending horizontally 5 across the conveyor, a presser roll immediately in advance of said knife, and a presser roll immediately behind said knife, said rolls being spaced apart slightly directly above the knife.

2. A sandwich bun slicing machine comprising 10 a frame, an endless belt conveyor therein, a cutter bar supported in said frame for reciprocation transversely of the conveyor, a common means in said frame for driving the conveyor and reciprocating the cutter bar, a halving knife carried by 15 said bar and extending transversely across and above the conveyor, a supplemental frame carried by the machine frame above said knife, means for adjusting the height of said supplemental frame with respect to the knife, and a plurality 20 of transverse presser rolls journaled in said supplemental frame in parallel slightly spaced relation parallel to said knife.
